United States Patent Office

Des. 221,423
Patented Aug. 17, 1971

221,423

CART BODY

Harold Douglas Seielstad, Jr., Birmingham, Mich., assignor to Midwest Aero Industries Corporation, Royal Oak, Mich.

Filed July 28, 1970, Ser. No. 24,192

Term of patent 14 years

Int. Cl. D12—02

U.S. Cl. D14—3

FIG 1

FIG 2

FIG 3

FIG. 1 is a perspective view of a cart body embodying the invention;

FIG. 2 is a rear view of the cart body of FIG. 1; and

FIG. 3 is a top plan view of the cart body of FIG. 1, with portions of the handle broken away for convenience of illustration.

The elements shown in broken lines are included for illustrative purposes only.

I claim:

The ornamental design for a cart body, as shown and described.
